Philip J. Mean,
ATTORNEY

spring-like character to tension their frictional holding engagement in the grooveways.

In practice the brush and comb combination may be sold with a series of different brush elements, such as a shampoo brush with nylon bristles and a similar brush with stiffer bristles which may be used as a head scratcher and to remove dandruff flakes from the scalp; also a similar brush with natural bristles for use as a nail brush and for general scrubbing or utility purposes. These several different kinds of brushes may be sold separately, to be used as such or to be slipped into place in the brush holder construction here disclosed.

What is claimed is:

A substantially flat and straight comb and brush back and handle having longitudinally extending, closely spaced, substantially parallel undercut grooveways in the lower face of the same with narrow slots opening from the grooveways through the underface of the flat back and handle, brush and comb elements slidably and removably engaged in said undercut grooveways in closely adjoining, side-by-side relation, said brush elements having wire cores with the ends

of the cores bent angularly into oposing relation, substantially cylindrical tubular members engaged over said opposed, angularly bent end portions of the cores, the undercut grooveways for holding said brush elements being substantially circular in cross section to frictionally receive and hold said cylindrical tubular members and the angularly bent end portion of the cores extending through said narrow, open slots and being thereby held by said slots and projecting from the underface of the back in closely adjoining relation to the comb element.
